UNITED STATES PATENT OFFICE.

ROBERT A. WHITE, OF MAPLEWOOD, NEW JERSEY.

DESIGN FOR A BRUSH.

43,174.

Specification for Design.

Patented Oct. 15, 1912.

Application filed June 11, 1912. Serial No. 703,084. Term of patent 7 years.

To all whom it may concern:

Be it known that I, ROBERT A. WHITE, a citizen of the United States, and a resident of Maplewood, Essex county, State of New Jersey, have invented a new, original, and ornamental Design for Brushes, of which the following is a specification, reference being had to the accompanying drawing, forming part thereof.

In the drawing Figure 1 shows a side

view of my improved design; Fig. 2 a plan view of the same; and Fig. 3 an end view of the same.

I claim:

The ornamental design for a brush as shown.

ROBERT A. WHITE.

Witnesses:

GEO. L. GIBSON,
W. B. GIBSON.
